United States Patent Office.

AIME NICHOLAS NAPOLEON AUBIN, OF MONTREAL, CANADA.

Letters Patent No. 99,130, dated January 25, 1870.

IMPROVEMENT IN PEAT-MOULDING MACHINES.

The Schedule referred to in these Letters Patent and making part of the same

I, AIME NICHOLAS NAPOLEON AUBIN, formerly of Albany, State of New York, temporarily residing in Montreal, Dominion of Canada, have invented certain Improvements in Peat-Moulding Machines, of which the following is a specification.

The nature of my invention consists in combining a water-trough, a floating inclined plane, with anti-friction rollers, a rocking pendent lever, a moulding-box, with a vertical diagonal side, a sliding catch-block, raised or lowered by a pedal-lever, and moving a push-bar, set in motion by a conveyer-rod bearing a fixed catch-block and a hinged cross, and operating in its forward and backward stroke, the whole for the purpose of bringing peat-moulds from return cars, wetting them, filling them with ground peat, and pushing them off to the spreading-cars on different tracks, thus securing more regular and rapid work, and relieving men from the exhausting labor of constantly lifting heavy weights.

Figure 1 represents, in perspective, the whole arrangement of the different parts.

Figure 2 shows the catch-blocks on a larger scale.

A is a trough, kept nearly filled with water. One end of it touches the empty mould-table; the other extends to all the tracks which may be found necessary for reaching every portion of the drying-grounds.

At the extremity, nearer the empty mould-table, is an inclined plane, B, provided with wooden rollers, and hinged at one end, so that the other end, by floating, adapts itself to the height of the water.

C, empty mould-table. It is provided with rollers at right angles with the inclined-plane rollers, in order to facilitate the motion of the moulds toward the moulding-table. Over the empty mould-table is a rock-shaft, D, with axles bearing upon the upright frames d¹ d². To that shaft is fixed a counterweighted lever, G, with pull-rope g at right angles, and a pendent frame, H, is also fixed to the shaft, at a right angle with the shaft itself and with the lever G.

I J is the moulding and conveying-table. It is composed of a frame, i¹, provided with rollers i², over which the moulds travel. That table is prolonged at J as far as desired, and crosses above all the tracks leading to the drying-grounds, and is furnished, wherever it crosses a track, with an arrangement for throwing off the passing filled moulds, at the will of the men attending the cars. The moulding-table is partially covered by the mould-guides j¹ j²; and at j³ is seen the moulding-box, which consists merely in three vertical boards, one of which, as seen in the drawing, is placed diagonally. Inside of the moulding-box, the upper part of the mould-guides, which partially cover the moulds, is cut so as to uncover the whole breadth of the passing moulds.

L is the conveyer-rod, which begins at l¹, and is pro-

longed to the end of the moulding-table. At l¹ it is bolted to a connecting-rod, which receives an alternate forward and backward motion, from the principal mover, by means of a crank, of a rack with geared pinion, of an eccentric cam, or any of the other well-known devices for that purpose.

l², crooked arm fixed to the conveyer-rod, passing over one of the mould-guides, and carrying, at its upper end, the hinged cross l³, which is so arranged as to rock over a mould in its backward motion, but to push it when it moves forward. At its free end, naturally held upward by the weight of the cross, it is provided with an eye, to which a rope can be attached, so as to keep the cross raised by the attendant, in case it is desired for a time not to propel the moulds. The conveyer-rod slides through brackets l⁴, firmly bolted to the side of the moulding-table.

M, railroad-tracks for the spreading-cars passing under the moulding-table.

N, swinging bar, hinged at one end to the table-frame, and at the other to the upright fork n¹, which is raised at will by the motion of the pedal-lever n².

l⁵, catch-block fixed to the conveyer-rod.

n³, catch-block sliding upon the swinging bar N, hinged so as not to move otherwise than up and down. It has an eye at n⁴, to which a rope, n⁵, is tied, which passes in the pulley n⁶, and has its other end fixed to the push-bar n⁷.

n⁷, push-bar doubled up, so as to have one branch sliding under the table in suitable guides, and the other over the rollers, so as to push the moulds sidewise from the mould-table rollers to the platform O.

n⁸, return pulley.

n⁹, counterpoise to bring back the push-bar.

O, platform, fixed or hinged to the moulding-table over each track, for receiving the filled mould pushed aside by the push-bar.

o¹ o² o³ o⁴ o⁵, peat-moulds. These are constructed with movable bottoms and cross-projections, and their operation is fully described in my patent of the 27th October, 1868.

The different parts, just described, and disposed relatively, as indicated, are calculated to facilitate and diminish hand-labor. Their operation will easily be understood. A car-load of empty moulds is brought on the track at M. The attendant throws them into the trough A, where a boy sinks them in the water, so as to wet them, and thus facilitate the parting of the peat, when they are overturned upon the ground. He then floats them to the inclined plane B, where the man, who feeds the moulds to the machine, draws them to the empty mould-table, and, when mould o¹ is back of the mould o², he draws the rope g, which, by means of the lever G and pendent frame H, throws the mould o³ on the moulding-table, when it is moved forward, by

the hinged cross ℓ^3 , during the forward stroke of the conveyer-rod L. The moulds thus conveyed, one pushing the other, pass under the mould-box j^3 , in which the ground peat, from the machine, falls. The diagonal side of the box forces the peat to spread in the mould rapidly, and with less resistance than a straight scraper or a roller requires. The filled mould o^5 is propelled by the following one, and comes in front of the platform v. If there be no car ready to load on that track, the mould travels further; but, if it is desired to load a car on the track M, the attendant places his foot upon the pedal-lever n^2 , the swinging bar N is raised, the sliding catch-block n^3 is caught by the block ℓ^3 , which is carried back during the last half of the backward stroke of the conveyer-rod L; the sliding block n^3 pulls the rope n^5 , which, in its turn, pulls the push-bar n^7 , which throws off from the moulding-table the filled mould o^5 to the platform O, from which, again, it is slid to the spreading-car by the men on each side of it. Each of the filled moulds weighs nearly two hundred pounds, and each of my ordinary peat-machines can fill from ten to fifteen moulds per minute, rendering necessary the use of mechanical appliances to rapidly handle such large quantities of material.

When the conveyer-rod L begins its forward motion, and before a mould has been pushed forward, the counterpoise, n^9 , draws back the rope passing over the return-pulley n^8 , and another not shown. The push-bar and the sliding catch-block are brought back, while the catch-block ℓ^3 recedes further, and releases the sliding block and pedal-lever, which allows the swinging bar to fall out of gear, until it is desired to throw off another mould.

I do not claim the moulds as constructed, nor the trough for wetting and floating them to the feeder, as these devices are fully described in my patent of 27th October, 1868.

What I claim as my invention, is—

The combination of the hinged inclined plane B, the rock-shaft D, lever G, conveyer-rod L, bearing the arm ℓ^3 , hinged cross ℓ^3 , and one or more catch-blocks ℓ^3 ; the throwing-off arrangement consisting in a pedal-lever, sliding catch-block, rope or chain, push-bar, and counterweight, the whole constructed and operating substantially as hereinbefore set forth.

N. AUBIN.
